UNITED STATES PATENT OFFICE.

GEORGE BAEHR, OF PITTSBURGH, PENNSYLVANIA.

MILL FOR ROLLING SHAPES.

Application filed July 31, 1918. Serial No. 247,659.

To all whom it may concern:

Be it known that I, GEORGE BAEHR, a resident of Pittsburgh, in the county of Allegheny and State of Pennsylvania, have invented a new and useful Improvement in Mills for Rolling Shapes, of which the following is a specification.

This invention relates to rolling mills. Among the objects of the invention are the provision of roll housings, in which two or more sets of co-operating rolls of different sizes may be mounted; the provision of means for positively connecting the rolls so that they will always turn in exact synchronism; means for adjusting and locking the rolls in proper circumferential registry; and means for feeding blanks to the rolls at different speeds, according to the size and shape of cross section of the finished part being rolled.

Referring to the drawings, Fig. 1 is an end elevation of the roll housing, adjusting and feeding mechanism; Fig. 2 is a diagrammatic illustration of the variable feed control motor; Fig. 3 is in part a side elevation and in part a central vertical section on the line 3—3 of Fig. 1; Fig. 4 is an inside elevation of the roll housing showing the mounting of one of the roll shafts therein; Fig. 5 is a detail elevation of a driving gear wheel adapted to be clamped on one of the roll shafts; Fig. 6 is a detail elevation of the gear wheel of Fig. 5, as applied to the shaft and with its adjusting means in place; Fig. 7 is a section on the line 7—7 of Fig. 6; and Fig. 8 is a section on the line 8—8 of Fig. 6.

In certain co-pending application, Serial No. 247,658, filed July 31, 1918, and Patent No. 1,289,602, I have described a composite roll having removable surface members adapted to form a finished bar, or a series of articles, of varying cross section. The rolled product may be a flattened or elliptical wire, having at intervals a round portion, or it may be in the form of a crowbar having a large head, a reduced body portion, and a smaller tapered handle, or it may be a string of spikes, chisels, punches, or many other shapes. Such rolls are highly efficient for finishing comparatively small articles of great length compared to their diameters, and of not too great difference in cross section between any two points.

Manifestly the circumference of each of

the co-operating rolls adapted to produce a finished article of varying cross section must be a multiple of the length of the article itself. For producing braces for aeroplane work, wherein the body is flattened or elliptical with round end portions adapted to be threaded, it is desirable to roll such braces as long as fifteen feet, thus requiring a roll approximately five feet in diameter to make a complete brace at each revolution. In making crowbars, or strings of chisels, spikes, or other such articles of much less length, the roll diameter may be much less than that necessary for aeroplane braces. Consequently, it is a distinct economy to be able to substitute rolls of different sizes in a single stand or housing, according to the finished work which is to be done. This avoids the waste of space, and duplication of equipment that would be necessary if a separate roll stand had to be provided for each class of work to be done.

One part of my invention deals with the provision of a roll support in which rolls of different sizes may be mounted and operated.

In rolling articles of varying cross section the faces of the two rolls have co-operating forming grooves which register together, the grooves in the two roll faces form a space of the same varying cross section as the finished article formed thereby in the rolling operation, and the changes of cross section of the groove in the roll faces must register accurately as the two co-operating rolls rotate. Therefore I have provided means for positively connecting the shafts of the two co-operating rolls by gear wheels, so that they must turn in exact synchronism, and so that neither one can lag behind the other or be moved out of registering relation by vibration or other causes in operation.

When the rolls are changed, and a new pair put in position, it is a rather delicate operation to secure the exact registry of corresponding portions of the varying forming grooves in the surfaces of the rolls, and therefore I have provided a micrometer adjusting means by which one of the rolls may be turned on its shaft, and locked in adjusted position, without disturbing the other roll, or the train of gears normally connecting the two roll shafts.

In rolling articles such as crowbars, for example, where the cross section of the fin-

ished article varies considerably at different points, as, for example, the head of the crowbar compared with the end of the tapered handle, it is advantageous to vary the feed of the hot metal bar or blank which is supplied to the finishing rolls for forming the article being manufactured. For this purpose I provide a feed mechanism controlled by an electric motor, which is driven at varying speed, in accordance with the cross sectional changes of the finished article being formed. For example, in making the thick head portion thereof the feed motor is driven rapidly, so as to push the hot blank into the rolls to aid in supplying a sufficient amount of metal for that portion of the crowbar. In the smaller octagon portion of the crowbar, where less metal is required, the motor is driven slower, so as to feed metal to the rolls at a reduced speed, about the speed of the rolls if the cross sectional area of the octagon portion is substantially equivalent to the cross sectional area of the bar being fed. When the rolls come to the smaller handle portion of the crowbar, where less metal is required in the finished article than is contained in the blank, the motor is retarded, so that the forming rolls have to pull the metal from the feed rolls, the latter having a retarding effect.

These results are attained by a construction one form of which is illustrated in the drawings.

The whole apparatus is mounted on a concrete foundation 1, in the usual manner. A metal base plate 2 is bolted into the concrete, and upon this is bolted the base 3 of the roll stand, which comprises four upright members, oppositely disposed in pairs, 4 and 5, connected at their tops by cross members 6 and 7. Fig. 1 shows an end view of the roll stand, one of each of the pairs of supports 4 and 5 being seen. It will be understood that similar supports 4 and 5 are situated at the other end of the roll stand, directly behind the members 4 and 5 in this figure.

The upright supports 4 and 5 have inner vertical faces 8, which at intervals have co-operating oppositely disposed horizontal notches 9 therein.

In this frame, forming rolls 10 and 11 are mounted, keyed properly to shafts 12 and 13. The lower roll 10 is keyed on a shaft 12, and the upper roll 11 is keyed on a shaft 13. Their faces are substantially in contact, in the usual manner, and carry removable segmental shaping members 14 formed with beveled edges adapted to be retained under a supporting beveled collar 15, and on one side removable clamping beveled ring 16, which on the other side is clamped to the side face of the roll by bolts 17, as more specifically described in my patent No. 1,289,602.

The rolls shown in the drawings are the largest which are adapted to be used in this particular stand.

The bearings 18 for shaft 12 seat upon transverse supports 20 between the upright frame members 4 and 5. Journal caps 19 rest on the bearings 18 and are held rigidly in place upon the supports 20, between the vertical supports 4 and 5 by means of cross members 21, which have lateral flanges 75 22 adapted to fit into notches 9 in supports 4 and 5, as shown clearly in Fig. 4. Screws 23, having locking nuts 24, extend through the cross members 21 and engage the tops of the journal boxes 19, in order to clamp them 80 rigidly down upon the support 20. The shaft 12 is extended to an outer bearing 25, mounted on the concrete foundation 1. The shaft 12 may be driven in any desired manner, as by a belt on pulley 26. A geared 85 connection to a motor or any driven shaft may be used.

The upper roll 11 is supported by cross members 27, exactly similar to the members 21, above described. Flanges 22 fit into the upper set of opposite notches 9, and retaining plates 28 are bolted on to the frame, and to the members 27, to hold the support in proper position. Journal boxes 29 enclosing bearings 30 for shaft 13 are supported on coil springs 31, which rest at their lower ends on cross members 26, as shown clearly in Figs. 1 and 3. The upper sides of the journal boxes 29 rest against the lower ends of abutment members 32, threaded in 100 the cross frame members 6, and held in rigid relation thereto by locking nuts 33, as shown in Fig. 3. This manner of mounting the bearings of shaft 13, permits an accurate adjustment of the roll 11 to contact 105 with the roll 10, as will be obvious.

The rolls may be adjusted axially to secure proper vertical alignment of the shaping grooves by means of set screws 28^a mounted in plates 28 and having their inner ends contacting against the bearings of the roll shafts, as shown in Figs. 1 and 3.

When it is desired to use rolls of smaller diameter in the same stand, the rolls 10 and 11 are taken out, and the desired rolls substituted therefor, and these bearings are supported by means of the supporting notches 9 which are provided at such intervals, as to accommodate a number of different sizes of rolls. As shown in the drawings, notches 120 are provided for use with a set of rolls of exactly one-half the diameter of the rolls 10 and 11.

In substituting the smaller rolls the cross supports 21 are moved up from the notch 125 in which they are shown engaged in Figs. 1 and 3, to the set of notches 9 just above their illustrated position, the support 20 is built up by blocks or otherwise to bring the journal boxes up to the new position of 130

supports 21, and the roll shaft is clamped in position by screws 23 as will be obvious.

The upper shaft is lowered by moving the transverse supports 27 to the set of notches 9 just below that in which they are illustrated in Figs. 1 and 3, and the abutment screws 32 are turned down to the new position, until the roll faces are held in proper contact. By this adjustment the feeding mechanism operates on the same level as with the first set of rolls. By having a feed which may be vertically adjusted, rolls of still different sizes can be substituted in this stand by mounting the lower 15 one of them in the position of shaft 12, without changing its position as shown in Fig. 3, and by mounting the upper roll one set of notches below the position of roll 11 as illustrated. The rolls which could be so 20 mounted would be between the larger and smaller sizes above referred to.

In order to secure the continuous exact registry of irregular forming grooves in the surfaces of the rolls it is necessary to have 25 the two roll shafts positively connected to each other. I have shown the roll shaft 12 as driven by the pulley 26. The other end of the roll shaft 12 is extended, and keyed thereon is a gear wheel 34, which meshes 30 with and drives a gear 35, which in turn drives a similar gear 36, which in turn drives a similar gear 37 fixed on shaft 13 of the upper roll. By this positive connection continuous synchronism in revolution of the 35 rolls is insured.

In order to permit the use of rolls of different sizes in the same stand, as above described, I mount the gears 35 and 36 on stub shafts 35^a and 36^a respectively, which 40 are slidably carried in horizontal ways 38 and 39, in extensions 40 of the vertical frame members 4. Referring to Fig. 1, when smaller rolls are substituted, thereby drawing the shafts 12 and 13 closer together, the 45 gears 35 and 36 are simply moved outward the required distance to permit the bringing together of shafts 12 and 13, and then clamped in that position. The result is simply to change the position of the four gears, 50 without in any way changing their positive interdriving relations.

In order to secure proper registering of the forming grooves in the faces of the rolls it is necessary to accurately adjust the rolls 55 as to circumferential relation thereof. This is done by turning the upper roll 11 to the required position relative to the lower roll, and locking it therein. In order to effect the necessary final and very accurate adjustment I provide special means, comprising a sleeve 41, which is fixed on the outer end of shaft 13 by a key. A circular flange or web 43 extends from the sleeve 41, and this web has bolt holes therethrough with bolts 60 44 therein, as shown in Figs. 6 and 7. The

web also has a concentric segmental slot 45, as shown in Fig. 6. At each end of this slot there is a projection or raised lug 46, through which there is a threaded hole in which is mounted a set screw 47. 70

Driving gear wheel 37 for the shaft 13 has a large central opening 48, adapted to fit loosely over the sleeve 41. The web 49 of this wheel has curved concentric slots 50 adapted to receive bolts 44 above described, 75 and a raised lug 51 adapted to extend through the curved slot 45 in web 43, when the gear wheel is placed in position on the sleeve 41, as shown in Fig. 7. In this position the adjusting screws 47 are adapted to 80 bear upon the sides of lug 51, and by advancing one screw and retracting the other, the lug may be adjusted to any desired position within the limits of its travel in slot 45. Consequently, with the sleeve 41 keyed 85 on shaft 13, by loosening bolts 44, to permit relative rotation of the gear wheel 37 and sleeve 41 and by advancing one screw 47 and retracting the other, the roll 17 may be turned, without movement of its driving 90 gear wheel 37, and the upper roll may be very accurately adjusted relative to the lower roll and locked in position. When this position is determined, and fixed by means of the said screws, bolts 44 are again 95 tightened so as to clamp the gear wheel 37 to the web 43, and to make the driving gear rigid with respect to the shaft of the roll. This construction permits a very rapid micrometer adjustment of the roll surfaces, 100 to secure exact registering of the forming grooves.

The feeding mechanism comprises an electric motor M having a shaft 52 which carries a pinion 53, driving gear 54, fixed 105 on the shaft 55, on which shaft is a smaller gear 56, which drives a large gear 57, keyed on the shaft of feed roll 58, which cooperates with a similar feed roll 59, as shown at the left of Fig. 1. A frame 60, 110 supports all of the members just above referred to, and is itself mounted on the concrete foundation 1. The upper roll 59 is yieldingly held by a coil spring 61, so as to maintain a grip on the metal stock, which 115 is being fed to the rolls.

Fig. 2 diagrammatically represents means for controlling the speed of motor M, and consequently of the feed rolls 58 and 59, to correspond to variations in the cross section 120 of the finished article being formed by rolls 10 and 11. In this diagram A represents the armature and F represents the field of electric motor M, above referred to. P represents a circular plate mounted on either 125 shaft 12 or 13, at any convenient point, and rotating therewith. Plate P is made of insulating material and carries on its exposed face segmental metal strips C, D, and E, and an outer annular strip B. A wire 130

4
G leads from the armature A to the continuous conductor ring B, and wire H leads from the other pole of armature A through the field F to the segmental contact strip C, with which it is adapted to be connected by a brush J. Branches L and K lead from wire H to contact brushes M' and N, adapted to connect with the segmental contact segments D and E respectively, during certain parts of a revolution of the plate P. The circular contact B is permanently connected to the segmental contact C, which in turn has permanent connections to contact segments D and E. The connection K includes a resistance element, and the connection L includes a greater resistance element, while in the continuous wire H there is no resistance.

In electric motors of the type shown weakening the field circuit causes the motor to speed up, as is well known. Consequently, by running the field current of the motor M through the wire H, as is the case when the brush J is in contact with strip C, the motor will tend to travel at its lowest speed, there being no resistance in the field. As the strip C passes out of contact with brush J, the brush M' will make contact with strip D, and resistance K will be thrown into the field circuit, immediately increasing the speed of the motor. Likewise when brush M' breaks its contact with strip D, and brush N connects with strip E, the full resistance L will be thrown into the field circuit, and the speed of the motor will be further increased. It will be understood that the control illustrated diagrammatically in Fig. 2 is intended for the rolling of a shape having a comparatively long small part, such as the handle of a crowbar, then a shorter enlarged portion, then a still further shorter enlarged portion. The result is to overfeed the roll during the formation of the heavy part of the finished article, and to underfeed it during the formation of the smaller part of the finished article. For rolling aeroplane braces and similar shapes there would be but two changes of speed, and those very slight, since the cross-sectional area varies but slightly in such work.

In connection with Fig. 1 I have shown a supplementary electric heating arrangement, comprising a generator R one pole of which is connected by wire S to the frame 3 of the finishing rolls; the other pole being connected by wire to the frame 60 of the feed rolls. The concrete foundation will ordinarily furnish sufficient insulation between the two metal roll frames, but if desired the frame 60 may be mounted on a fibre mat 70 and the bolts holding the frame to the concrete suitably insulated in well known manner. Also the wires S and T 65 may be connected to the rolls 10 and 59

direct by brushes on the shafts. But ordinarily this is not necessary.

Current will thus flow from the feed rolls to the finishing rolls through the metal stock and that portion of it between the rolls 10 70 and 59 will be heated thereby. This re-heating feature is of value where very small bars are being rolled, thus offsetting the tendency of such small bars to cool rapidly.

By the construction and arrangement 75 above described I provide a roll stand in which finishing rolls of various sizes may be mounted, the change being easily made. Also means for positively driving both rolls of the pair by a geared connection, which 80 insures continuous registering of the roll faces in a definite relation to each other. Also adjustable means for turning one of the rolls without removing it from its bearings, to secure proper initial registering of the 85 surfaces; and also means for varying the feed during a part of each revolution of the finishing rolls. The many uses and advantages of these features will be apparent to those familiar with the art. 90

I claim:

1. A roll stand comprising a base and two pairs of vertical parallel members rising therefrom, and journal bearing supports adapted to be attached to the vertical members at different points vertically, whereby to mount pairs of rolls of different sizes in the same frame. 95

2. A roll stand comprising two pairs of vertical parallel members, the members of 100 each pair being provided on their inner faces with oppositely positioned roll supports arranged to carry pairs of rolls of different sizes with their faces in contact.

3. A roll frame comprising two pairs of 105 parallel upright members, the members of each pair having co-operating notches therein, and cross members adapted to fit into said notches to support roll journal boxes thereon, said notches being provided at different 110 elevations to support pairs of rolls of different sizes.

4. A frame for supporting finishing rolls having geared drive wheels and intermediate connecting gear wheels, comprising vertical 115 supporting members having means to carry said rolls at different heights, a horizontal member attached to the upright members adapted to carry the intermediate gear wheels and to permit the adjustment of said 120 gear wheels at various distances from the vertical frame, whereby to move the said intermediate gear wheels out of the path of the gear wheels on the shafts of the finishing rolls, when said rolls are raised or lowered. 125

5. A frame for housing gear driven finishing rolls comprising vertical members having means for supporting rolls at various heights therein, and a horizontal member attached to the frame and adapted to carry a 130

supplementary gear wheel connecting the driving gear of the finishing rolls.

6. A frame for finishing rolls comprising vertical supporting members, means to support rolls at different heights in the frame, shafts carrying said rolls, gear wheels on said shafts, intermediate gear wheels meshing with each other and with the gear wheels on the roll shafts, and means to move the shafts of said intermediate gear wheels horizontally with respect to the supporting frame, whereby to permit the raising and lowering of the finishing rolls therein.

7. The combination with finishing rolls of

a vertical supporting frame for the rolls, 15 said frame being adapted to support in operative position pairs of rolls of different sizes, said rolls having operatively connected thereto driving gears, a horizontal frame attached to the main frame and carrying thereon intermediate gears meshing with each other and with the driving gears of the rolls, said intermediate wheels being mounted in the horizontal frame so as to be slideable therein.

In testimony whereof I have hereunto set my hand.

GEORGE BAEHR.
